DESIGN FOR A COMBINED LIPSTICK HOLDER AND EYE SHADOW CASE

Florence N. Lewis, New York, N. Y.

Application July 8, 1941, Serial No. 101,953

Term of patent 7 years

To all whom it may concern:

Be it known that I, Florence N. Lewis, a citizen of the United States of America, residing in New York city, county of New York, and State of New York, have invented a new, original, and ornamental Design for a Combined Lipstick Holder and Eye Shadow Case, of which the following is a specification, reference being had to the accompanying drawing, forming part thereof, wherein—

I claim:

The ornamental design for a combined lipstick holder and eye shadow case, substantially as shown.

FLORENCE N. LEWIS.
